US00D759924S

(12) **United States Design Patent**
Masalin et al.

(10) **Patent No.:** US D759,924 S
(45) **Date of Patent:** ** Jun. 21, 2016

(54) **ICE SCRAPER**

- (71) Applicant: **Fiskars Garden Oy Ab**, Billnäs (FI)
- (72) Inventors: **Petteri Masalin**, Pinjainen (FI); **Mikko Heine**, Pinjainen (FI); **Teemu Sandelin**, Pinjainen (FI); **Mika Sokka**, Pinjainen (FI)
- (73) Assignee: **Fiskars Garden Oy Ab**, Billnäs (FI)
- (**) Term: **14 Years**
- (21) Appl. No.: **29/525,457**
- (22) Filed: **Apr. 29, 2015**

(30) **Foreign Application Priority Data**

- Oct. 30, 2014 (EM) 001429039-0002
